HANDLE BAR FOR A MOTORCYCLE OR OTHER VEHICLE

Avery F. Weaver, 21030 Le Fever, Warren, Mich. 48091

Filed Jan. 9, 1967, Ser. No. 5,357

Term of patent 14 years

(Cl. D90—11)

FIG. 1

FIG. 2

FIGURE 1 is a front elevational view of the handle bar for a motorcycle or other vehicle showing my new design; and

FIGURE 2 is a side elevational view thereof.

The hand grips, controls and portion of the stem, shown in broken lines, are included for illustrative purposes only.

I claim:

The ornamental design of a handle bar for a motorcycle or other vehicle, substantially as shown and described.
